UNITED STATES PATENT OFFICE.

PAUL HOLLADAY WAGGENER, OF COLUMBIA, KENTUCKY.

ENVELOP.

1,155,388.

Specification of Letters Patent.

Patented Oct. 5, 1915.

Application filed August 12, 1914. Serial No. 856,439.

To all whom it may concern:

Be it known that I, PAUL H. WAGGENER, a citizen of the United States, residing at Columbia, in the county of Adair and State of Kentucky, have invented a new and useful Envelop, of which the following is a specification.

The device forming the subject matter of this application is an envelop adapted to be assembled with a calendar or other card which is long enough to project beyond the envelop, novel means being provided whereby the envelop may be held upon one end of the card and whereby, at the same time, the flaps of the envelop may be maintained folded, it being possible to detach the envelop from the card, and to refold and to seal the envelop.

In the drawing:—Figure 1 is a plan wherein the envelop is shown folded and assembled with a card; Fig. 2 is a section on the line 2—2 of Fig. 1; Fig. 3 is a plan of the envelop in the form of a blank; Fig. 4 is a plan showing a portion of the opposite face of the blank from that delineated in Fig. 3; Fig. 5 is a plan showing a modified form of tab; Fig. 6 is a plan showing a still further modification in the tab; Fig. 7 is a plan showing a modified form of blank out of which the envelop may be fashioned.

The envelop forming the present invention embodies a central portion 3, opposed flaps 4 and 8, and opposed flaps 6 and 7, the flap 4 being provided with an adhesive indicated at 5. Carried by the flap 8 is a severable tab 9 which may be equipped with an adhesive substance.

The flap 4 is folded inwardly onto the central portion 3 as indicated by the arrow A in Fig. 3, the flaps 6 and 7 are folded inwardly onto the flap 4, in the direction of the arrows B and the flap 8 is folded upwardly in the direction of the arrow C to overlie the flaps 6 and 7.

The invention embraces a card 1 which upon one face may carry a calendar 2. One end of the card 1 is inserted between the folded flap 4 and the folded flaps 6 and 7, the calendar 2 lying adjacent the flap 4. The adhesive tab 9 on the flap 8 is then attached to the rear face of the card 1, the device appearing as shown in Fig. 1.

Upon the outer face of the central portion 3, the address of a merchant may be inscribed, as shown at 50 in Fig. 4. The per-

son receiving the card 1 and the folded envelop, in the condition shown in Fig. 1, severs the tab 9 and moves the envelop from the card. The envelop may then be unfolded into the condition shown in Fig. 3, whereupon an order may be inscribed on that face of the blank which is disclosed in Fig. 3. Thereafter, the envelop may be folded up, the flap 4 being sealed down by the adhesive 5.

As shown in Fig. 5, the flap 8^a is provided with a pair of tabs 9^a which are perforated as shown at 10.

In Fig. 6, the tab 9 is adhesively attached to the flap 8' and is adapted to engage adhesively with the card as before.

In Fig. 7, the flap 8^b is shortened and tapered, and terminates in an adhesive tab 9^b.

In the form of envelop shown in Fig. 6, the tab 9' is attached to the flap 8' not being formed integral therewith, the same being mucilaged upon one side so as to adhesively engage the flap 8' and also provide a means for attachment to the card 1.

In the construction shown in Fig. 7, the flap 8^b is of lesser length than the flaps 8, 8' and 8^a as heretofore described, the same having a tapered edge terminating in the integral flap 9^b which corresponds to the flap 9 heretofore described.

From the foregoing description, taken in connection with the drawings, it is evident that with an envelop constructed according to the present invention, that the parts will be properly held upon the card 1 so as to protect the calendar or other advertising device, and yet be readily and easily removed to permit of the formation of the same into a sealed envelop either for containing correspondence or for constituting a correspondence card or envelop of itself.

By providing the small tabs for properly holding the flap 8 in place, the flaps 6 and 7 are locked upon the card 1 and thus the present device with no other connection than the tab 9 will remain properly assembled upon the card 1.

What is claimed is:

1. An envelop blank having a rectangular central portion, four flaps, one extending from each edge of the central portion the two opposite flaps being short with substantially parallel outer edges, one of the longer flaps carrying adhesive upon its free edges, and an adhesive carrying tab projecting from one edge of the remaining long flap,

- whereby when the two short flaps and the adhesive carrying longer flap are folded against the central portion and an article of greater length than the central portion is slipped between the two short flaps and such folded long flap, the remaining long flap incloses the opposite face of the article and the short flap and the parts are held so folded by the tab adhesively engaging the article.
- 10 2. The combination with a card, of an envelop comprising a body and free flaps, the body shielding one end of the card and the other end of the card being exposed beyond the body, the flaps being folded with respect to the body and the card, one flap being provided with a severable tongue con-

nected to the card thereby to maintain the flaps folded and to hold the envelop detachably upon the card to permit a removal of the envelop from the card; and means for 20 securing the flaps in closed positions with respect to the body, after the tongue is severed, and after the envelop has been re-folded independently of the card.

In testimony that I claim the foregoing 25 as my own, I have hereto affixed my signature in the presence of two witnesses.

PAUL HOLLADAY WAGGNER.
